UNITED STATES PATENT OFFICE.

JOSEPH MERRITT, OF HARTFORD, CONNECTICUT, ASSIGNOR TO THE HARTFORD LOCK RING COMPANY, OF HARTFORD, CONNECTICUT, A CORPORATION OF CONNECTICUT.

RING-Straightening Mechanism.

1,161,001.

Specification of Letters Patent. Patented Nov. 16, 1915.

Application filed April 4, 1912, Serial No. 638,462. Renewed May 25, 1915. Serial No. 30,464.

To all whom it may concern:

Be it known that I, JOSEPH MERRITT, a citizen of the United States, residing at Hartford, in the county of Hartford and State of Connecticut, have invented a new and useful Improvement in Ring-Straightening Mechanism, of which the following is a specification.

It is common practice in the art of making rings in large quantities to wind the wire or tube from which they are made into a spiral coil and then cut the coil along one side. This, however, leaves the rings twisted spirally so that the ends of each ring are not opposite one another.

The present invention relates to a mechanism which is designed to receive a coil of wire or tube and hold it while it is being cut along one side for the purpose of separating the turns of the coils and forming the rings.

The object of this invention is to provide a simple and easily operated mechanism of this class which holds the coil in a desired manner while it is being cut along one side, and which can be quickly manipulated after the cut has been made in such manner as to simultaneously straighten all the rings, that is, twist them so as to bring the ends of the rings opposite each other.

In carrying out this invention there is a holder with a recess adapted to receive the coil of stock from which the rings are to be formed. There is a fixed rack with teeth which project into the recess on one side, and two movable racks with teeth that project into the recess on the opposite side. The movable racks are separated so as to allow a saw to rotate between them for cutting the coil. The racks are first in such relation that when the coil is placed in the recess the rack teeth will extend between the turns after the manner of a screw thread, and then after the saw has made its cut, one movable rack is forced in one direction, and the other movable rack is forced in the opposite direction. The teeth of the racks moved in this way simultaneously and uni-

formly carry the severed ends of the rings so that the ends of each ring will be alined. 50

Figure 1 of the accompanying drawings shows a plan of mechanism which embodies the invention with the parts in the positions occupied when the spiral coil is first placed in the recess, a portion of the slides bearing 55 the movable racks being broken away to expose a section of the coil. Fig. 2 is a similar view with the slides moved so as to straighten the rings. Fig. 3 is a view of a section of the magazine bar with a few rings. 60 This bar is employed for holding the rings while they are being straightened, and it provides means whereby all of the rings may be removed together in condition to be fed into another machine for subsequent 65 manipulation. Fig. 4 shows a plan on larger scale of a short piece of coil severed for forming the rings. Fig. 5 shows a side view of the same with the magazine bar in place. Fig. 6 shows an edge view of one 70 of the rings before it is straightened. Fig. 7 shows an edge view of a ring after it has been straightened. Fig. 8 shows a side view of a straightened ring. Fig. 9 shows a coil from which the rings may be formed. Fig. 75 10 shows a view of the inner face of one of the members of the straightener. Fig. 11 shows an end view of the member shown in Fig. 10. Fig. 12 shows a view of the inner face of the other member of the straightener. Fig. 13 shows an end view of the member shown in Fig. 12. Fig. 14 shows a side elevation of the straightener and the cutting saw with parts broken away to show the construction. Fig. 15 shows a trans- 85 verse section on the plane indicated by the dotted line 15—15 on Fig. 14.

The holder which is illustrated is formed of two members 1, 2, which are detachably held together by dowel pins 3. Near the 90 upper edges in the inside faces of these members of the holder are longitudinally extending curved grooves 4, 5. When these two members of the holder are put together, these grooves form the recess in which the 95 coil 6 is placed and clamped. Secured to

the inner face of one member of the holder, preferably to the member 2 by screws 7 is a plate 8 which has a rack on its upper edge. The teeth 9 of this rack project into the bottom of the coil recess.

Movably secured on the top of the holder member 1 is a slide 10. Stud screws 11 passing through slots 12 hold this slide in place and guide it when it is moved. Movably secured to the top of the holder member 2 is a slide 13 that is held by screw studs 14 that pass through slots 15. These slides are spaced a distance apart approximately equal to the thickness of the cutting saw 16 which is mounted on the arbor 17, and which when the cut is being made extends down between the slides into the recess. On the edge of the slide 10 is a rack with teeth 18 that project into the recess on one side of the saw, and on the edge of the slide 13 is a rack with teeth 19 that project into the recess on the other side of the saw.

Fastened to the opposite ends of each of the members of the holder is a bracket 20, and turning in each bracket is a screw 21. These screws may be provided with clamp nuts 22 if desired. The screws may be turned against opposite ends of the slides, for holding the slides in position and for moving them longitudinally with relation to each other and to the holder.

The spirally coiled wire or tube from which the rings are to be formed is located in the recess, the slides being adjusted so that the teeth of the racks which they carry enter between the turns of the coil in the manner of screw threads. When the coil is in place and is held by the rack teeth, either the holder is moved beneath the saw, or the saw is moved along the holder as desired for cutting the coil along one edge between the two movable racks and severing the turns into independent rings 23. After this cut has been made by the saws or other suitable means, one of the slides may be forced in one direction and the other slide may be forced in the opposite direction. As the fixed rack holds the rings near the middle on one side of the recess and the two movable racks engage the rings at their ends on the other side of the recess this movement twists all of the rings and straightens them from the shape shown in Fig. 6, to the shape shown in Fig. 7, in which the ends are in alignment with each other. For the purpose of retaining the rings, a rod 24 with a feather 25 may be thrust into the recess, the rod passing inside of the rings and the feather between the ends. The rod and feather are desirably inserted into the rings just after the saw has made the cut and before the rings are straightened so that when they are twisted for straightening they will

not collapse or have their ends jammed together. This rod and feather may also be conveniently employed for removing the rings all at one time in such position that they can be conveniently fed to another machine for subsequent operation. After the rings have been straightened, the two members of the holder are separated, allowing the rings to be taken out strung on the rod.

The invention claimed is:

1. A ring straightening mechanism having a holder with a recess adapted to receive a coil of stock, a fixed rack projecting into said recess and adapted to engage the turns of the coil on one side, two racks with a saw space between them projecting into said recess and adapted to engage the turns of the coil on the opposite side, and means for moving said last mentioned racks longitudinally with relation to each other and to said fixed rack for straightening the rings.

2. A ring straightening mechanism having a holder with a recess adapted to receive a coil of stock, and three racks projecting into said recess so as to engage the turns of the coil, one of said racks being fixed and two of said racks being movable longitudinally with relation to each other and to said fixed rack for straightening the rings.

3. A ring straightening mechanism having a holder with a recess adapted to receive a coil of stock, a rack with teeth projecting into said recess fixed to the holder, and racks with teeth projecting into said recess movable longitudinally on the holder.

4. A ring straightening mechanism having a holder with a recess adapted to receive a coil of stock, slides movable longitudinally on the holder, a rack with teeth projecting into said recess fixed to the holder, and racks with teeth projecting into said recess carried by the slides.

5. A ring straightening mechanism having a holder with a recess adapted to receive a coil of stock, slides movable on the holder, screws for moving the slides, a rack with teeth projecting into said recess fixed to the holder, and racks with teeth projecting into said recess carried by the slides.

6. A ring straightening mechanism having a sectional holder with a recess adapted to receive a coil of stock, a slide movably mounted on each section of the holder, a rack with teeth projecting into said recess fixed to the holder, and a rack with teeth projecting into said recess carried by each slide.

7. A ring straightening mechanism having a sectional holder with a recess adapted to receive a coil of stock, a slide movably mounted on each section of the holder, a rack with teeth projecting into said recess fixed between the sections of the holder, a

rack with teeth projecting into said recess carried by each slide, and means carried by the holder for moving the slides.

8. A ring straightening mechanism having a holder with a recess adapted to receive a coil of stock, a stationary rack with teeth projecting into said recess, and movable racks with teeth projecting into said recess.

9. A ring straightening mechanism hav-

ing a holder with a recess, a pair of slides, 10 means for moving the slides in opposite directions, a rack with teeth projecting into said recess carried by each slide, and a fixed rack with teeth projecting into said recess.
